(57) **CLAIM**

The ornamental design for a fiber optic Christmas tree novelty, as shown and described herein.

DESCRIPTION

FIG. 1 is a front elevational view of a fiber optic Christmas tree novelty showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is an enlarged sectional view showing in detail the fiber optic aspects of the claimed design.
